UNITED STATES PATENT OFFICE.

PHILIP C. ARNOLD, OF EAST HAMPTON, CONNECTICUT, ASSIGNOR TO THE BEVIN BROTHERS MANUFACTURING COMPANY, OF SAME PLACE.

BELL.

SPECIFICATION forming part of Letters Patent No. 651,431, dated June 12, 1900.

Application filed October 4, 1897. Serial No. 653,984. (No model.)

To all whom it may concern:

Be it known that I, PHILIP C. ARNOLD, a citizen of the United States, and a resident of East Hampton, in the county of Middlesex

5 and State of Connecticut, have invented certain new and useful Improvements in Bells, of which the following is a full, clear, and exact description, whereby any one skilled in the art can make and use the same.

10 The object of my invention is to provide means whereby a yielding pressure shall be insured on the strikers of a bell-striking mechanism at all times; and to this end my invention consists in the details of the several parts 15 making up the structure as a whole and in the combination of such parts, as hereinafter described, and more particularly pointed out in the claims.

Referring to the drawings, Figure 1 is a 20 plan view of a bell having striking mechanism embodying my invention with the gong removed. Fig. 2 is a side view of the same. Fig. 3 is a detail view, on enlarged scale, showing the striker-bar. Fig. 4 is a side view of 25 the same. Fig. 5 is an end view of the same. Fig. 6 is a side view, on enlarged scale, of the striker-bar with the spring-plate and strikers in place. Fig. 7 is a top view of the same, showing the parts in one position of assembly. Fig. 8 is a like view showing the parts in the 30 final step of assembly.

In the accompanying drawings the letter *a* denotes the base of a bell; *b*, the post; *c*, the striker-bar, rotatively mounted thereon, and 35 *d* the lever for rotating the striker-bar. Strikers *e* are loosely mounted on the striker-bar, and a striker-plate *f* is used for exerting a yielding pressure upon the strikers for the purpose of causing the perfect operation thereof. Prior to my invention in this form of bells 40 the striker-plate *f* has been mounted on the post *b* either directly or indirectly and the ends bearing with a yielding pressure upon the strikers; but in use it has been found that 45 these striker-plates are apt to become distorted, so that little or no spring action is exerted on the strikers. By the use of my invention hereinafter described this defect is entirely avoided. The strikers *e* have a slot 50 *e'* for the purpose of allowing a movement radially of the base, a lug *g* being struck from the substance of the plate and passing through

or into the slot *e'* and a lug *c'* also extending into the slot in the striker, these two lugs limiting the movement of the striker in both directions. 55

In carrying out the invention the lug *g* has formed thereon a head *g'*, the metal forming this lug being cut to the required shape, so that the head shall lie crosswise of the striker-bar *c*. A slot *f'* is formed in the striker-plate *f* crosswise thereof and in a position to register with the head *g'* of the lug *g*, that is passed through the slot in the striker-plate as the parts are assembled. The head *g'* is then 60 turned in a position at right angles to that first assumed, and, as shown in Fig. 8 of the drawings, the head in this instance overlying the top surface of the striker-plate and preventing any excessive upward movement to 65 an extent to destroy its spring action. 70

It is obvious that other means for holding the striker-plate may be employed and yet come within the scope of my invention; but the means herein described are preferred. 75

I claim as my invention—

1. In combination in a bell-striking mechanism, a rotary striker-bar, a striker mounted thereon, a striker-plate overlying the striker and having an elongated slot of uniform width therein, and a lug from the striker-bar passing through the striker and having a T-shaped head adapted to pass through the slot in the striker-plate and to lie crosswise thereof. 85

2. In combination in a bell-striking mechanism, a rotary striker-bar, a striker loosely mounted thereon, a striker-plate overlying the striker and having a slot of uniform width therein, and a lug from the striker-bar having an elongated head adapted to pass through the slot in the plate and overlying the same. 90

3. In a bell-striking mechanism, in combination, a rotary striker-bar, a striker loosely mounted thereon, a striker-plate overlying the striker and having a slot therein, a lug upturned from the striker-bar, extending through the striker-plate and having an elongated head greater in length than the shortest distance across the slot in the striker-plate. 95 100

PHILIP C. ARNOLD.
